FIG. 5.

Inventor:
John F. Thomas,
By L. M. Hurlow
Atty.

UNITED STATES PATENT OFFICE.

JOHN F. THOMAS, OF PEORIA, ILLINOIS, ASSIGNOR OF ONE-HALF TO WILLIAM F. SCHAFER, OF ELKHART, ILLINOIS.

ROBE-RAIL.

1,305,179.

Specification of Letters Patent. Patented May 27, 1919.

Application filed May 26, 1917. Serial No. 171,161.

To all whom it may concern:

Be it known that I, JOHN F. THOMAS, a citizen of the United States, residing at Peoria, in the county of Peoria and State of Illinois, have invented certain new and useful Improvements in Robe-Rails; and I do hereby declare that the following is a full, clear, and exact description of the invention, which will enable others skilled in the art 10 to which it appertains to make and use the same.

This invention relates to a robe rail. It relates more particularly to improvements in robe rails for attachment to vehicles.

15 Robe rails are usually secured to the backs of vehicle seats and it is my purpose to provide a robe rail including in its construction means whereby robes or other articles may be positively clamped and locked in such a 20 way as to make it impossible to remove them without the operation of a lock to release them.

25 The main object of the invention, therefore, is to provide a new form of robe rail having an adjustable part for permitting the insertion and removal of a robe, coat, or other article, which will firmly clamp them, providing a suitable form of lock so that 30 after the articles have been clamped in place they cannot be removed by thieving persons.

35 Other objects and advantages will appear herein, aided by a study of the accompanying drawing, which shows one adaptation of the invention, it being understood that the device is susceptible of minor changes without departing from the inventive idea, such changes lying within the meaning of the accompanying claim.

40 Figure 1 is a rear elevation of a vehicle seat, showing my robe rail attached thereto.

Fig. 2 is a transverse sectional elevation of one of the parts which carries the rail.

45 Fig. 3 is a transverse section of the rail and its parts.

Fig. 4 is a longitudinal sectional elevation; and,

Fig. 5 is a horizontal section of parts shown in Fig. 3.

50 A indicates a seat back, for example, to which may be attached the rail or from which it may be suspended. The said rail is indicated as a whole by the reference character B. C, C indicate any ordinary form of bracket attached to the seat, and

55 D, D indicate hangers for carrying the rail,

the same being pivotally suspended from said hangers or brackets, for example.

Each member D is recessed at its lower end at E and preferably has a depending 60 extension E' for overlying and covering from view the ends of the rail. The described recess E in each member is preferably inwardly curved or arched, as clearly shown in Figs. 2 and 3, and is adapted to receive an arc shaped metal portion F. G is a second arc shaped portion preferably having extended flange portions H at its edges whose upper surfaces abut against the edges of the described portion F, the structure being such as to leave a recess J between the two described portions, said recess extending the full length of the rail and opening into a recess K in each of the members D.

55 L are suitable devices for securing the two portions together and connect them to the members D in the described recesses E. In the present instance these devices are in the form of screws extending through both 80 said portions F G into the said members D.

M indicate two ratchet bars each adapted to move longitudinally within the recesses K of the members D, being provided on their inner facing surfaces with a series of teeth N. O is a bar which may be solid or tubular in form slotted at its ends as indicated at P, one extremity of each ratchet bar extending into one of the described slots, 90 said ratchet bars being held in said bar by means of screws or rivets Q, there preferably being fillers R in the ends of the bar O, if the latter is hollow, through which the described screws or rivets Q extend.

95 The bar O may be provided on its upper surface with a series of pits S adapted to enter complementary notches or sockets T in the under surface of the portion G, the purpose of which will appear later herein.

100 Within the recess J are two longitudinal movable pawls U shown in plan in Fig. 5, one end of each of which extends into the recesses K of each member D adapted to engage the teeth N of the ratchet bar M. 105 The inner adjacent ends of the pawls U are pivotally connected to a member V pivoted to the upper surface of the portion G for example, the pivots for the pawls lying equidistant from the pivot of the member V, 110 the line of the pivots lying transversely of the said portions F and G.

- The recess E in one of the members D is extended or deepened as at W and on the pawl U of that particular member is a lug 2 which extends upward into said recess W.
- 5 3 is indicative of any suitable form of lock preferably one of the barrel type including wards, not shown, which will require a special form of key for the operation of said lock. Extending from the barrel, for example, is a depending tongue 4 adapted to engage the described lug.
- 5 indicates any desired or suitable type or form of spring attached in this instance at one end to one of the pawls U and at its 15 other end to some fixed portion of the structure, such, for example, as a pin 6 fixed in the portion G.
- It is now observed that by inserting the key and turning the barrel 3 to the right the 20 tongue 4 will move the pawl U having the lug 2 from engagement with the teeth of the ratchet bar at that side and due to the described structure the opposite pawl U will be retracted by moving in the opposite 25 direction thereby freeing the ratchet bars M so that they may be drawn outward. In their normal positions, of course, the pawls are in engagement with the teeth due to the described spring 5.
- 30 The free ends of the pawls are beveled downwardly and inwardly as viewed in the drawing and the teeth N are beveled outwardly and upwardly so that the bar O may be pushed toward the portion G without 35 hindrance by the pawls, a movement of the pawls manually being required through the lock in order to release the said bar O so that it can be moved in the opposite direction.
- 40 I preferably provide means for limiting the outward draw on the ratchet bars or the separation of the bar O so that the parts will not become separated. The means may include a spring 7 secured in a recess 8 in 45 each member D, the free end of the spring carrying an enlargement 9 adapted to enter a recess 10 in each ratchet bar, the recess 8 in each instance being of sufficient depth to permit the spring 7 and its enlargement 50 9 to be moved back into it when the ratchet bars are pushed inward, said enlargements 9 coming into play when the bar O has been drawn out to its limit by entering said recesses 10.
- 55 The extremities of the pawls may be suitably guided in their movements to properly engage the ratchet bars and whereby they will have no lateral movement, any suitable means being provided to this end such, for 60 instance, as pins 11 within the recess J between which the pawls move. Preferably

the under surface of the portion G is furnished with a covering of cloth, rubber, or other material G' to prevent rattling when the robe rail is not in duty.

65

The robe or other article is inserted between the bar O and the portion G and said bar forced against the article as far as it will go, the pawls automatically engaging the proper teeth.

70

The large surface clamped by the bar O positively prevents the withdrawal of the article in addition to which the described covering G', and the tits S and sockets T, if used, assist. The ratchet bars are preferably pivoted to the bar O so that the latter can be easily changed in position without binding and the said bar will readily accommodate itself to a bulky portion of the article that may chance to lie near one end 80 of the said bar, which bar may lie at an angle to the portions F, G.

75

If the ratchet bars and the bar O were rigidly related it would be necessary to at all times have the bar O parallel to the 85 portion G in order to adjust it since the said ratchet bars would bind and chock within the sockets of the members D.

80

If desired the lock need not be used and merely employ the clamping feature to prevent the article slipping from the rail.

85

Having thus described my invention, I claim:

A device of the class described comprising in its construction a pair of supporting 95 hangers each provided with a bore, a member connecting them rigidly and having a grooved under side, mechanism concealed in the member including a pawl extending into each of the said bores, manually controlled means to retract both the pawls simultaneously, a ratchet-bar slidably in the bore of each hanger and each having a recess near its innermost end, means to elastically hold the pawls normally in engagement with 105 the teeth of the ratchet bars, a rail pivoted at its ends to the ratchet bars adapted to snugly seat in the grooved under side of the described member for holding an article, and a spring latch secured in each hanger 110 adapted to engage in the recess of an adjacent ratchet bar, the latches adapted to prevent the ratchet bars from separating from the hangers when the bar is drawn outwardly.

115

In testimony whereof I affix my signature, in presence of two witnesses:

JOHN F. THOMAS.
